UNITED STATES PATENT OFFICE.

JOSEPH LACASSAGNE AND RUDOLPHE THIERS, OF LYONS, FRANCE.

IMPROVED APPARATUS FOR REGULATING AND MEASURING THE INTENSITY OF ELECTRIC CURRENTS.

Specification forming part of Letters Patent No. **19,642**, dated March 16, 1858.

To all whom it may concern:

Be it known that we, JOSEPH LACASSAGNE and RUDOLPHE THIERS, of Lyons, in the Empire of France, have invented an Electro-Metric Regulator for Electric Telegraphing, Lighting, and Electro-Motive Purposes; and we do hereby declare that the following is a full, clear, and exact description of the same, reference being had to the annexed sheet of drawings, making a part of the same.

Our invention relates to an apparatus for rendering electric currents regular and constant, whatever may be the variations in the battery employed; also, for regulating the intensity of the electric current to any extent required, and for indicating the amount of dynamical electricity expended upon any kind of work.

This apparatus is founded upon the combination of the following three well-known principles: First, when a galvanic current is made to pass through a liquid that is less conducting than the wires of the battery, the intensity or quantity of electricity set in motion in a given time is inversely proportional to the resistance which it experiences passing through the liquid, and this resistance may be regulated either by increasing or diminishing the conducting powers of the liquid, or by increasing or reducing the number of contact-points immersed in the same; second, when the surfaces of the conductors immersed are of such metal as is not attacked by the liquid—platina, for instance—gases may be obtained in the free state which are evolved by decomposition of the liquid by the electric current, the quantity of gas obtained being proportional to the intensity of the current or to the quantity of electricity to which the immersing-liquid has given passage; third, the attracting power of an electro-magnet varies, *ceteris paribus*, in the same proportion as the intensity of the current which creates the same.

Having thus set forth the leading principles upon which our apparatus is constructed, we will now briefly describe the way in which they may be combined and applied so as to form a regulating apparatus.

Let us suppose one of the conducting-wires of a working battery to be cut in two, each of the extremities carrying a platina plate, both being suspended inside a glass bell of a gasometer or gas-holder containing water, that has

been rendered conducting by being slightly acidulated with sulphuric acid. Thus, according to one of the principles above stated, the gasometer will rise or sink according as the gas evolved is let out of or kept in the same. The rising of the bell will produce a constant diminution of intensity by reducing the surface of platina immersed, while the reverse effect will take place if by letting the gases issue the bell is made to sink, and thus the points of contact between the platina and the intervening liquids are increased. There is also an electro-magnet having an armature with a lever, the fulcrum of which is placed on one of the branches of the electro-magnet, and a spring or sliding weight being applied to one of the ends of the lever. The current being sent through the coil, the magnetic attraction will act contrarily to said spring or weight, and overcome its force or not, according as the one or the other is greater.

To complete this apparatus, one of the coils which is to act upon the armature is bored out cylindrical inside, and through this coil passes a tube which communicates with the inside of the bell of the gas-holder. The end of the armature thus shutting or opening this tube, it may be made to act as a valve. Thus, the spring tending to draw down the opposite end of the armature, if the magnetic attraction is more powerful than the force of the spring the armature will be in close contact with the mouth of the tube, and the gas, thus being prevented escaping, raises the gasometer bell and plates out of contact; hence the intensity of the current transmitted and the magnetic power in the coils above mentioned is diminished till the latter equals or is less than the tension of the spring, when the armature end rises from the pipe-mouth above mentioned and allows some gas to escape until the current becomes again strong enough to slant the pipe, and the same action is repeated over again, thus affording a means of regulating the force of the current by the spring or weight balancing the magnetic attraction of the coils.

In order to avoid the rapid oscillations of the armature, which is attracted by the spring and electro-magnet alternately, we use a cock or tap for letting out the gases evolved in the inside of the bell of the gasometer. By trying the position of this tap, it may be set to any

opening required so as to let out the same quantity of gas constantly that would be let out intermittently by the oscillations of the armature. The gases thus escaping may be conducted into a graduated test-glass, which is put down upon a hydro-pneumatic trough, and, by using a table of electro-chemical equivalents when the battery is used for electrotyping, the quantity of gold, silver, or other metal deposited in a given time may be ascertained or read off from the scale of the test-glass.

The accompanying drawings will bear out what has been said above, showing Figure 1 an elevation, and Fig. 2 a plan, of the electro-metric regulator.

The same letters of reference stand for like parts in both figures.

A B C D is the framing of the regulator; F, copper reservoir containing a bell filled with acidulated water, for keeping the liquid of the gas-meter always at the same level; G H I, cocks and tubes by means of which the acidulated water is made to pass from the reservoir F into the gas-meter; J, glass reservoir containing acidulated water; K, glass bell for receiving and collecting the gases resulting from the decomposition of water; L, copper thimble, which is hermetically luted upon the bell K; M N, small pipes through which the two conducting-wires O P pass, the latter being wound with silk and cemented in the former; Q R, platina plates that are attached to the conductor O P; S T, tube passing into the interior part of the electro-magnet U V. This electro-magnet has a coil of copper wire, wound with silk as usual, the end X of said wire communicating with the conducting-wire P, and the other with the plate v, to which it is secured by a set-screw, V. Y Z, armature for shutting and opening the orifice of the tube S T. a is a set-screw for regulating the travel of the armature Y Z. b represents a nut and screw for regulating the tension of the coiled

spring c; d, scale showing the actual tension of said spring by means of a hand, e; f g h, india-rubber tubes which are secured to the taps placed at i j respectively. These taps are for giving passage to the gases formed in the bell K. l, india-rubber tube for conducting the gases that are evolved in the bell K into a test-glass, s; m, square of a tap, the opening of which is regulated by the button n, which gears into the sector o p; q, hand for showing upon a divided arc, r, the amount to which the tap m is opened, so as to show the different quantities of gas that pass into the test-glass s in a given time; s, test-glass, that is graduated so as to show the cubic contents of gas which has been collected from the gasometer J K; t, small hydro-pneumatic trough; u, copper plate to which the conducting-wire O is secured by a set-screw; v, copper plate to which the conducting-wire P is secured. The regulator is placed on one of the conducting-wires of the working-battery by means of these two plates, so that the current must necessarily pass through the regulator. A' B', cord and counter-weight, passing over pulleys and regulating the pressure exerted by the gasometer-bell; E' F', small brass rods that slide in tubes for guiding the bell K in its ascending and descending motion.

What we claim as our invention, and desire to secure by Letters Patent, is—

Combining the application of the three principles herein specified so as to form an apparatus for regulating and measuring the force or intensity of the electric current produced by any battery, and applicable to telegraphing and motive purposes, substantially as herein set forth.

J. LACASSAGNE.
RPHE. THIERS.
